UNITED STATES PATENT OFFICE.

GEORGE MIDDLETON EDWARDS, OF LONDON, ENGLAND.

METAL LATH.

SPECIFICATION forming part of Letters Patent No. 412,917, dated October 15, 1889.

Application filed May 14, 1888. Serial No. 273,882. (No model.) Patented in England August 27, 1883, No. 4,127.

To all whom it may concern:

Be it known that I, GEORGE MIDDLETON EDWARDS, of London, England, have invented certain new and useful Improvements in 5 Metal Laths, of which the following is a specification.

The present invention constitutes the subject-matter of Letters Patent granted to me in Great Britain, No. 4,127, dated August 27, 10 1883.

My improved laths are made entirely out of sheet metal, and their distinguishing feature consists in their being provided with an attaching-rib and with laterally-extending 15 flanges, said flanges being in a different plane from the back of said rib.

The improved laths are illustrated in the accompanying drawings, in which—

Figure 1 shows the preferred construction 20 of lath in side, plan, and end elevation. Fig. 2 shows a modified construction of the lath in side, plan, and end elevation; and Fig. 3 shows the improved laths applied to the rafters of a building.

25 Referring first to Fig. 1, A represents the projecting rib of the improved lath, and B B represent the side flanges thereof. The central projecting rib extends longitudinally of the lath throughout its entire length, and, as 30 shown, comprises a flat attaching-web a, and side walls b b, which connect the web of the rib with the laterally-extending flanges B B. These flanges B B extend in a different plane from the web a, but in a plane parallel with 35 that of the web. The side walls b b of the projecting rib are preferably inclined toward each other, so that the open space between the edges of the side walls, where they are connected with the side flanges, is narrower than the width of the web a. Owing 40 to this arrangement the rib is dovetailed in cross-section. The outer edges of the laterally-extending flanges B B are notched, as shown at c c, throughout their entire length.

45 The notches c c of one side flange alternate with those on the opposite side flange in order to economize material in stamping the laths out of sheet metal. The projecting ears of one flange fit into the notches of the adjacent 50 flange of the adjoining lath, which is simultaneously formed out of the piece of sheet metal. In using laths made in this manner

the attaching-web a of the projecting rib A is placed against the rafter, and the lath is attached to the rafters by driving a nail or 55 nails through the web into the rafter. The several laths are thus placed side by side on the rafters, as shown in Fig. 3, a sufficient space being left between adjoining laths for the mortar to pass between. When mortar 60 is applied to these laths, it is securely held by them, since it fills into the space between the rafters and the laterally-extending flanges B B of the laths. The mortar also fills 65 in the dovetailed rib, and when hardened in this position the dovetailed rib prevents the mortar from falling out. The notched edges of the side flanges of the lath materially assist in the holding of the mortar and permit 70 the mortar to freely flow behind the flanges. 75

The modification shown in Fig. 2 shows a lath having the essential features of a projecting rib having an attaching-web and laterally-projecting flanges in different planes. The sides of the lath are also formed with inwardly-extending notches having the same 80 function as the notches shown in the preferred construction. In this construction the projecting rib has but one side wall connecting the flanges with the web. The rib is formed from the sheet-metal blank by first 85 bending the single side wall b of the rib down at right angles to the body of the blank, and then by bending the web a at right angles to the side wall b. The body of the blank, which constitutes then a single side flange b, has a series of slits cut into it, said slits extending nearly, but not quite, to the side wall b. The tongues d d, which are 90 formed by these slits, are then bent through an angle of one hundred and eighty degrees to the opposite side of the side wall of the projecting rib, thus constituting the second side flange B. The spaces formed by the bending over of the tongues d d constitute a series of notches in the first-formed side flange, and the spaces separating the several tongues d d from each other constitute the notches on the second formed side flange. The laths thus formed require less metal than those of the preferred construction; but they are not 95 so strong.

The laths of the modified construction are applied in the same manner as those of the

preferred construction, the attaching-nails passing through the web of the lath.

I claim as my invention—

- 5 1. A sheet-metal lath comprising a longitudinally-extending projecting rib having a flat attaching-web, and laterally-extending notched flanges extending in a plane different from that of the attaching-web but parallel therewith, substantially as set forth.
- 10 2. A metallic lath having a longitudinally-extending dovetailed projecting rib having

a flat attaching-web, and laterally-extending notched flanges extending in a different plane from that of the attaching-web but parallel therewith, substantially as set forth. 15

In testimony that I claim the foregoing I have hereunto set my hand this 8th day of June, 1887.

GEORGE MIDDLETON EDWARDS.
